UNITED STATES PATENT OFFICE.

GEORGE EDWARD NORTHRUP, OF STAMFORD, CONNECTICUT, ASSIGNOR, BY MESNE ASSIGNMENTS, TO PITNEY-BOWES POSTAGE METER COMPANY, OF STAMFORD, CONNECTICUT, A CORPORATION OF DELAWARE.

DIE PROTECTOR.

Application filed June 27, 1923. Serial No. 648,041.

To all whom it may concern:

Be it known that I, GEORGE E. NORTHRUP, a citizen of the United States, residing at Stamford, in the county of Fairfield and 5 State of Connecticut, have invented certain new and useful Improvements in Die Protectors; and I hereby declare that the following is a full, clear, and exact description thereof, reference being had to the accompanying drawings, which form part of 10 this specification.

This invention relates to a novel die protector especially designed to protect the dies of postage meter and mail marketing machines, such as shown in the patent to 15 Arthur H. Pitney #1,370,668, dated March 8, 1921, and the object of the invention is to provide a novel die protector adapted to surround the dies on the printing members of 20 said meters for the purpose of preventing any fraudulent attempt to obtain impressions from the printing member die when same is in its normal position of rest, and without revolving the die spindle, thereby 25 recording the amount of the impression on the meter.

I will explain the invention with reference to the accompanying drawings which illustrate one practical embodiment thereof 30 to enable others, skilled in the art, to adopt and use the same, and will summarize in the appended claims the novel features of construction, and novel combinations of parts, for all of which protection is desired.

25 In the drawings:

Fig. 1 is a front elevation of the printing member of a meter such as shown in said Pitney patent and showing my novel die protector attached thereto.

40 Fig. 2 is a side elevation of Fig. 1.

Fig. 3 is a plan view of a sheet metal blank from which my novel protector is formed.

45 Fig. 4 is a section on the line 4—4 Fig. 1. My novel die protector is illustrated in the drawings in connection with the printing member of a postage meter and mail marking machine, such as shown in the patent of Arthur H. Pitney #1,370,668, 50 dated March 8, 1921, in which 1 is the printing member or printer, the side face of which is provided with the suitable dies for printing the stamps on the letter or other mail matter, and is also preferably

provided with the usual stamp cancelling 55 lines, as described in the aforesaid patent. The printing member 1 is mounted on a vertical spindle 1^a which is rotated by suitable means within the base 2. Spindle 1^a is mounted in suitable bearings on the hollow base member 2 (which base houses the spindle and meter actuating mechanisms, not shown). Integral with the member 2 or securely attached thereto is a standard 2^a having an arm 2^b on its upper end provided 60 on its outer end with an upper bearing 2^c for the spindle 1^a. On the upper face of the base 2 is the lower bearing 2^d for the spindle, said spindle being rotated by suitable mechanism (not shown) within the base 65 2, as described in said Pitney patent. Mounted on spindle 1^a, above the printing member 1, is the letter guide wheel 1^b.

My novel die protector, as shown in Fig. 3, is preferably formed from a sheet metal blank or stamping, having a base portion 3^b, a head portion 3^k and a central narrow connecting portion 3^a of suitable length, connecting the base and head portions. The portion 3^b has a central opening 3^c on the 75 longitudinal axis of the part 3^a, and is provided, as shown, with a convex portion 3^d, substantially semi-circular in shape, and of slightly larger radius than the radius of the printing member 1, also with a concave 80 portion 3^e, and with a straight portion 3^f as shown, and integral with the base 3^b intermediate the concave and convex portions 3^d, 3^e, is a tongue or finger 3^g, of slightly greater length than that of the portion 85 3^a, the outer end of tongue 3^g being adapted to fit into a slot 3^h in the head 3^k, slot 3^h being symmetrically located with respect to the tongue 3^g. As shown, head 3^k is in 90 general shape and form symmetrical with 3^a and of same size as the base 3^b, and is provided with a convex portion 3^d, concave portion 3^e, and straight portion 3^f, and is also provided with the central opening 3^c of slightly larger diameter than the diameter 95 100 of the spindle 1^a.

The base and head portions of the blank or stamping 3, are adapted to be bent upwardly at right angles to the part 3^a on the dotted lines a—a, b—b (Fig. 3), and the tongue 3^g is then adapted to be bent towards the head 3^k, at right angles to the base 3^b, on the dotted line c—c (Fig. 3), so that

the outer end of tongue 3^e will enter the slot 3^h in the head 3^k , with tongue 3^e parallel with the part 3^a , and head 3^k parallel with the base 3^b .

5 When the blank 3 is bent as above described, the tongue 3^e will be parallel with the portion 3^a , and will extend between the base 3^b and head 3^k , the outer end of said tongue passing through the slot 3^h , and the 10 protector is then ready to be attached to the spindle 1^a to protect the printing member 1. As shown in Figs. 1 and 2, the base 3^b is placed on the top face of bearing 2^a , with the spindle 1^a passing through the 15 central hole 3^c therein, spindle 1^a further passing through the hole 3^c in the head portion 3^k . The die protector is preferably securely and non-rotatably attached to the top of the bearing 2^a by means of a pin or 20 rivet 4, passing through a perforation 4^a in the base of the protector 3^b , and into the top face of the bearing 2^a ; before the protector is thus fastened into position by 25 means of rivet 4, the protector should be turned or adjusted to the desired position relatively to the printing member 1; that is, the straight edge portions 3^f of the base and head should be adjusted so that portions 3^f are parallel with, and adjacent to, the 30 line of travel of the mail matter through the machine. The rivet or pin 4 should lock the protector in this position on the meter casing 2, and effectively prevents the protector from revolving either by accident 35 or by intent on the part of the operator, thereby preventing any fraudulent attempt to obtain impressions from the printing member on a letter or other mail matter unless the spindle 1^a is revolved and thus 40 recording the amount of the impression on the meter of the machine.

When the protector is properly positioned around the printing member as above described and as shown in Fig. 4, the protector 45 will effectively prevent the taking of an impression from the die without revolving the spindle 1^a , since the convex portions 3^g of the base and head are of greater radius than the face of the printing member 1, and the convex and straight portions 3^e , 3^f , lie entirely within the face of the printing member 1, as shown in Fig. 4. When 50 the printing member is normally at rest the die is in the position shown in Figs. 1 and 2, with the printing face thereof adjacent to and facing the standard 2^a . The projecting edges of the base and head 3^b , 3^k , and the parts 3^a and 3^g , will prevent anyone from obtaining an impression from the 55 die of the printing member, when the same is at rest. When, however, the printing member is revolved into the line of travel of the mail matter through the machine the die thereof passes between the convex edge portions 3^e and the straight edge portions

3^f , the base and head and the face of the die being of greater radius than the portions 3^e , 3^f , said die face will contact with the mail matter passing by the printing member 1 parallel with the edges 3^f of the 70 protector.

While I have shown and described the invention as applicable to a postage meter machine as shown in the said Pitney patent, it will be obvious that the invention 75 could be readily adapted for use with other types of machines, and therefore I do not consider the invention restricted to use with the said Pitney machine.

What I claim is:

1. For a machine of the character specified, a die protector, comprising parallel base and head portions connected by an intermediate portion, said base and head each having a circular opening at their centers, and the edges thereof having concave, convex, and straight portions; and said base having a tongue portion extending from the edge thereof intermediate and convex and concave portions, and said head having a 90 slot adapted to receive the end of said tongue portion; said protector being adapted to be placed around the die with the shaft of said die passing through the circular openings in the base and head portions.

2. For a machine of the character specified, a die protector, comprising parallel base and head portions connected by a relatively narrow intermediate portion, said base and head each having a circular opening at their centers, the edges thereof having concave, convex, and straight portions, and said base having a relatively narrow tongue portion extending from the edge thereof intermediate the convex and concave portions, and said head having a slot 100 adapted to receive the end of said tongue portion; said protector being adapted to be placed around the die with the shaft of 105 said die passing through the circular openings in the base and head portions, said protector being non-rotatably mounted with the straight edge portions of the head and base parallel and adjacent to the normal line 110 of travel of the matter passing through the machine to be stamped.

3. For a machine of the character specified having a revolvable spindle carrying a printing die; a protector having perforated base and head portions of greater diameter than the die and loosely surrounding the spindle; and a member connecting the head and base portions adapted to cover the printing surface of the die when the latter is in its normal position of rest; and means for fastening the protector so that it can not revolve.

4. For a machine of the character specified having a revolvable spindle carrying 120

25

30

35

40

a printing die; a die protector formed of sheet metal having a base portion and a head portion of approximately greater diameter than the die and loosely surrounding the spindle, and a member connecting the head and base portions and formed integral therewith, said connecting portion covering the printing surface of the die when the latter is in its normal position of rest; and means for fastening the protector so that it can not revolve.

5. For a machine of the character specified having a revolvable spindle carrying a printing die, a protector having perforated base and head portions of greater diameter than the die and loosely surrounding the spindle, and a member connecting the head and base portions adapted to cover the printing surface of the die when the latter is in its normal position of rest, one of said portions having a tongue spaced from the connecting portion and adapted to

engage the other portion; and means for fastening the protector so that it can not revolve.

6. For a machine of the character specified having a revolvable spindle carrying a printing die; a die protector formed of sheet metal having a base portion and a head portion of approximately greater diameter than the die and loosely surrounding the spindle, and a member connecting the head and base portions and formed integral therewith, said connecting portion covering the printing surface of the die when the latter is in its normal position of rest, and one of said portions having an integral tongue spaced from the connecting portion and adapted to engage the other portion; and means for fastening the protector so that it can not revolve.

In testimony that I claim the foregoing as my own, I affix my signature.

GEORGE EDWARD NORTHRUP.
